UNITED STATES PATENT OFFICE

JOSEPH B. PLATT, OF NEW YORK, N. Y.

DESIGN FOR A FOUNTAIN PEN HOLDER

Application filed February 19, 1931. Serial No. 38,727. Term of patent 3½ years.

To all whom it may concern:

Be it known that I, JOSEPH B. PLATT, a citizen of the United States of America, residing at New York city, in the county of New York and State of New York, have invented a new, original, and ornamental Design for a Fountain Pen Holder, of which the following is a specification, reference being had to the accompanying drawing, forming a part thereof.

The figure is a view in perspective of a fountain pen holder showing my new design, which is a spherical body of glass having an inverted conical recess in which a rotative pen-holding frame is mounted and the whole resting upon a shallow cylindrical base.

I claim:

The ornamental design for a fountain pen holder, substantially as shown and described.

JOSEPH B. PLATT.
